(57) CLAIM

The ornamental design for a spa and pool faceplate, as shown and described.

DESCRIPTION

FIG. 1 is a top view of a spa and pool faceplate showing my new design;

FIG. 2 is a top perspective view thereof; and,

FIG. 3 is a side view of one side thereof.

The ornamental design, which is claimed, is shown in solid lines in the drawings.

The features shown in broken lines depict environmental subject matter only and form no part of the claimed design.
